CONTAINER

George D. Snyder, Brooklyn, N. Y., assignor to
 American Can Company, New York, N. Y., a
 corporation of New Jersey

Application September 10, 1936, Serial No. 100,187

3 Claims. (Cl. 206—1)

The present invention relates to a sheet metal container or can having a removable element which may be the can cover, and has particular reference to devices associated with the removable element for supporting an article of manufacture such as an electric light bulb or the like so that the article may be readily removed from the devices for use when the removable element is separated from the can and so on that the article may be held confined within the can and spaced away from the walls thereof for shipment and storage when the removable element is applied to the can, the removable element providing a convenient means for readily inserting the supported article into the can and withdrawing it therefrom when desired.

The invention contemplates a sheet metal can for electric light bulbs and may be utilized as an automobile light bulb kit in which one or more light bulbs may be contained separated from the walls of the can. In the case of a can holding a plurality of bulbs the latter are separated from each other as well as from the walls of the can to prevent breakage during shipment and storage. The invention also contemplates such a can for light bulbs other than automobile bulbs and for articles of manufacture other than light bulbs.

An object of the invention is the provision of a sheet metal can having a removable element such as a cover or the like which is provided with yieldable clamping devices for supporting and holding an article of manufacture such as an electric light bulb or the like, the article being readily disengaged from the devices for use when the removable element is separated from the can and also being rigidly supported in the can out of contact with the can side walls when the removable element is applied to the can for shipment and storage.

Another object is the provision in such a can of article supporting devices which are adapted to hold articles such as electric light bulbs or the like having different shaped bases so that the same supporting device may be utilized for holding different forms of articles of the same class.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a can embodying the instant invention, the can being

provided with a removable cover at each end and having one of the covers shown removed and spaced relative to its end;

Fig. 2 is an enlarged vertical section taken substantially along the line 2—2 in Fig. 1 and showing both end covers in place on the can, and electric light bulbs shown in dot and dash lines held in place by clamping devices secured to the covers;

Fig. 3 is a horizontal section taken substantially along the line 3—3 in Fig. 2; and

Fig. 4 is an enlarged composite perspective view of one of the can covers including its article clamping device and the base of an electric light bulb showing how the latter may be readily inserted or detached from the clamping devices, parts of the bulb being broken away.

As a preferred embodiment of the invention the drawing discloses a sheet metal container comprising a tubular body 11 having removable elements which are preferably cover members 12. Each cover is formed with a top wall 13 and a depending side wall or flange 14 which preferably extends down outside of and adjacent the wall of the body when in position thereon. The marginal edge of the flange 14 of each of the covers terminates in a curl 15 which, when the covers are on the body, seats against an outwardly projecting bead 16 formed in the body wall adjacent each end of the body 11.

Threaded elements are formed in both body and covers and these elements cooperate to draw the flange curls 15 into tight engagement with the body beads 16 when the covers are applied. These threaded elements include a plurality of spaced interrupted thread sections 18 which may be struck inwardly from the cover flanges 14 and which are disposed at an angle.

Cooperating outwardly struck interrupted thread sections 19 may be formed in the wall of the body 11 between the beads 16 and the ends of the body. These thread sections are also disposed at an angle to correspond with the cover thread sections. The thread sections in the body and cover flanges are relatively short so that the thread sections of the cover may pass directly between the thread sections of the body when the covers are first applied.

A depending projection 21 formed at one end of each of the thread sections 19 provides a locking lug which holds the engaged threads in interlocked position as shown in Fig. 2, this being after the covers have been applied to the body and have been rotated into locked position. This general form of thread connection is often

used in sheet metal cans for securing can and cover together.

Rotation of the covers is facilitated by suitable knurling 22 formed in the cover flanges 14. 5 This knurling permits a more secure grip on the covers when they are being rotated into closed position or removed therefrom.

An article holding device or metal clamp bracket 25 is disposed in each of the covers 12, this 10 device being preferably formed to support electric light bulbs of the type used in automobiles. Each of the brackets comprises a U-shaped member constituting a light socket open on two sides, the bracket being formed with a bottom horizontal wall 26 (Fig. 4), and two upwardly extending diametrically opposed vertical legs 27. These legs are curved in horizontal cross-section to partially surround and yieldably engage 15 against the usual base 28 of a light bulb 29 when the latter is inserted into the socket. The natural springiness of the metal legs due to the cut away construction of the bracket, provides a resilient or yieldable socket for the bulb and obviates the necessity for employing supplemental 20 springs. Each bracket may be secured to the cover by a rivet 30 which extends through the bottom wall 26 of the bracket and the wall 13 of the cover.

The wall of each of the legs 27 is formed with 25 outwardly struck bayonet joint sections comprising a vertical section 31 (Fig. 4) which extends to the top edge of the leg and a horizontal section 32 which communicates with the lower end of the vertical section. These bayonet sections are of 30 sufficient dimension to accommodate the usual oppositely disposed locking pins 33 on the sides of the base 28 of the light bulb 29. A deep depression 34 located at the terminal end of the horizontal section 32 serves as a lock into which 35 the pins 33 are snapped when the light is inserted into the socket and is rotated into locking position as in the usual manner of inserting a bulb into an automobile headlight.

Some light bulbs are provided with a disc 35 40 (shown in dotted lines in Figs. 2, 3 and 4) which is secured to the light base 28 and is used in place of the pins 33 for locking the light into an automobile headlight. Provision is made as an additional element in the holding devices 25 for this 45 type of light base. Horizontal extensions 36 are formed on the legs 27 at their upper edges, these extensions projecting outwardly from the legs 27 as shown in Figs. 2, 3 and 4.

The outer edge of each of the extensions 36 is 50 formed with a hook-like flange 37, the wall of the flange being bent upwardly and thence inwardly providing a recess 38. The flange is further bent upwardly and outwardly providing a resilient beveled flange part 39. These hook-like flanges 55 37 are curved horizontally to conform to the shape of the disc 35 so that the latter may be snapped over the inclined flange parts 39 into position in the recesses 38. In this inserted position the light bulb is securely held against inadvertent displacement.

The brackets 25 in each of the covers 12 are 60 identical in construction so that either of the types of light bases mentioned may be held in them. Thus if desired one light of each kind may 65 be held in the pair of covers 12.

This construction of holding devices provides

a simple and rigid means of separately supporting at least two light bulbs or other similar articles so that they will not engage against the side of the can or against each other, thereby materially insuring against breakage during shipment and storage. The construction also provides a compact container which may be easily carried around and which affords ready access to the bulbs by removing one of the covers and disengaging the desired bulb from its socket in the usual manner of disengaging such bulbs from the sockets of automobile headlights. In this respect the can provides a convenient light bulb kit for automobiles.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container for electric light bulbs and the like, comprising a tubular body open at one end, a detachable closure for said end and a U-shaped bracket secured to said closure, said bracket including a plurality of separate pairs of diametrically opposed resilient leg members each arranged to hold a light bulb within the body spaced away from the walls thereof, one pair of said leg members being radially offset outwardly relative to another pair of said members to provide a greater area between said first mentioned pair of leg members, said pairs of leg members being located concentrically with respect to each other to exclude the use of one pair when the other pair is in use, one of said pairs of leg members having means thereon for resiliently holding the base portion of a light bulb of one conformation, the other pair of said leg members having means thereon for resiliently holding the base portion of a light bulb having a different conformation.

2. A container provided with means for selectively holding any one of a plurality of different types and sizes of replacement light bulbs, comprising a tubular body open at one end and having a diameter substantially equal to the diameter of a light bulb to be contained therein, a detachable closure for said end, and bracket means secured to said closure, said bracket means including a plurality of means of different structural characteristics respectively located to selectively hold light bulbs of different types in substantially the same position within said body.

3. A container provided with means for selectively holding any one of a plurality of different types and sizes of replacement light bulbs, comprising a tubular body open at its opposite ends and having a diameter substantially equal to the diameter of a light bulb to be contained therein, detachable closures for said ends, and bracket means secured to each of said closures, each of said bracket means including a plurality of means of different structural characteristics respectively located to selectively hold light bulbs of different types in substantially the same position within said body.

GEORGE D. SNYDER.
